DESIGN FOR A COAT

Margaret Richey and Philip Mangone, New York,
N. Y., assignors to Hat Corporation of America,
Norwalk, Conn., a corporation of Delaware

Application April 18, 1941, Serial No. 100,489

Term of patent 3½ years

To all whom it may concern:

Be it known that we, Margaret Richey and Philip Mangone, citizens of the United States, residing, both, at New York, county of New York and State of New York, have invented a new, original, and ornamental Design for a Coat, of which the following is a specification, reference being had to the accompanying drawing, forming a part thereof, and in which:

Figure 1 is a front view of the coat, embodying our design.

Figure 2 is a rear view of the coat, shown in Figure 1.

The characteristic feature of our design resides in the provision on the coat disclosed of the tapering panel-like flaps of the configuration shown, starting at the armhole seams and extending to the waist, said flaps being continuations of the front with the outer edges thereof free and overlapping the side front as shown.

We claim:

The ornamental design for a coat, as described and shown.

MARGARET RICHEY.
PHILIP MANGONE.
